United States Patent Office.

H. PALMERLEE, OF GRAND RAPIDS, MICHIGAN.

Letters Patent No. 86,315, dated January 26, 1869.

IMPROVEMENT IN FARM-GATES.

The Schedule referred to in these Letters Patent and making part of the same.

To all whom it may concern:

Be it known that I, H. PALMERLEE, of Grand Rapids, in the county of Kent, and State of Michigan, have invented certain new and useful Improvements in Farm-Gates; and I do hereby declare that the following is a full, clear, and exact description thereof, reference being had to the accompanying drawings, and to the letters of reference marked thereon, which form a part of this specification, and in which—

Figure 1 represents a perspective view, and

Figure 2, side view of my farm-gate.

Similar letters indicate like parts in both figures.

The nature of my invention consists in providing the upper end of a gate-post with notches over which works a metal strap, for the purpose of raising and lowering the gate, in combination with other devices, the peculiarity of which will hereinafter be described.

To enable others to make and use my invention, I will now describe its construction and operation.

In the accompanying drawings—

A A' represent two posts, secured to each end of a sill, B, or they may be secured in the ground.

C is a vertical bar, hinged to the post A', and provided at its upper end with the metal strap a.

This strap works into the notches a' a' a', formed on the gate-post D.

On the lower end of this post are secured two brackets b b, one on each side, to allow the gate-post D to slide up and down on the bar C when the gate E is raised or lowered.

The other gate-post F is provided with the latch d, working into a mortise formed on the inner surface of the post A.

This latch is provided with the spring e, which consists of the metal bar e', secured at its lower end to one of the bars of the gate, and the other end resting against a pin secured to the latch d.

Having thus fully described my invention,

What I claim as new, and desire to secure by Letters Patent, is—

The vertical-hinged bar C and metal strap a, in combination with the gate-post D and notches a' a' a' on its upper end, all constructed, arranged, and operated substantially as and for the purpose set forth.

In testimony that I claim the foregoing as my own, I affix my signature, in presence of two witnesses.

H. PALMERLEE.
